UNITED STATES PATENT OFFICE

2,266,617

REFRIGERATOR CABINET

Carl H. Steenstrup, Schenectady, N. Y., assignor
to General Electric Company, a corporation of
New York

Application September 18, 1940, Serial No. 357,265

7 Claims. (Cl. 62—89)

My invention relates to refrigerator cabinets. The refrigerated compartment of a household refrigerator is usually maintained at an average temperature of approximately 40° F. to 45° F. for general refrigeration purposes. An average temperature within this range may be maintained in the refrigerated compartment by the convection currents of air set up therein by a cooling unit or a refrigerant evaporator located in the upper portion of the refrigerated compartment. In the usual refrigerator, best results are obtained by maintaining the temperature of the surface of the evaporator considerably below freezing as, for example, 20° F. During operation of the refrigerator, and as the air is cooled, a considerable amount of the moisture present in the air circulated in the refrigerated compartment is removed. Inasmuch as the evaporator surface presents the coldest surface in the refrigerated compartment, this moisture is deposited on the evaporator walls in the form of frost. When a door attached to the evaporator is employed to close the front end of the evaporator, the accumulation of frost may eventually build up to such an extent that operation of the door is obstructed.

Accordingly, it is an object of my invention to provide an improved arrangement of the cooling unit and a door therefor which is simple in construction, and in which the aforementioned obstructing action of any frost accumulation on the cooling unit is minimized.

While the range mentioned above is satisfactory for the preservation of food in general, certain types of food such, for example, as meat and fish may be more satisfactorily preserved in a storage atmosphere having a lower temperature range. A storage atmosphere having a temperature range between 30° F. and 34° F. is more suitable for the preservation of meats and fish. Accordingly, many refrigerators of the domestic type are provided with a meat pan disposed immediately below the evaporator. It is another object of my invention to provide a new and improved support for such a food storage receptacle.

The space between one or both sides of the evaporator and the walls of the refrigerated compartment are frequently utilized for storage space by providing a shelf or shelves adjacent the evaporator. It is still another object of my invention to provide new and improved means for supporting such a shelf or shelves as well as the food storage receptacle.

The accumulation of ice on the walls of the evaporator has been referred to above. It has

been customary to defrost the cooling unit or evaporator, when necessary, as by stopping operation of the refrigerating machine until the temperature within the refrigerated compartment rises sufficiently to melt the ice and frost or by operating the evaporator through a comparatively long defrosting cycle, as between limits of approximately 19° F. and 50° F., for example. It is another object of my invention to provide means for assisting in the disposal of water resulting from such melting and any particles of ice or frost which may drop from the cooling unit and guard against such water and ice falling onto the articles stored within the refrigerated compartment.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a front elevational partial view of a refrigerator of the household type illustrating an application of the principles of my invention; Fig. 2 is an enlarged perspective view illustrating the details of the meat pan and shelf support shown in Fig. 1; and Fig. 3 is a perspective enlarged view illustrating the method of supporting the evaporator door of Fig. 1.

Referring to the drawing, I have illustrated a refrigerator 10 provided with an evaporator 11. A food storage receptacle 13 is supported below the evaporator 11 by means of a support or frame 14 defining an opening for receiving the receptacle, the frame being supported from the walls of the food storage compartment as, for example, by means of a plurality of rods 15 attached at the upper end to the top wall of the refrigerated compartment and at the other end to the frame 14. A closure member 12, carried by one of the rods 15, is provided for closing the open front end of the evaporator. The frame 14 is also provided with means, as a laterally extending flange 16, to assist in the support of shelves 17 disposed in the space between the side walls of the evaporator 11 and the side walls of the food storage or refrigerated compartment 19.

Describing my invention in greater detail, I have provided a household type refrigerator 10 having thermally insulated walls including an inner liner 18 defining a food storage compartment 19. A door opening in the front wall of the cabinet is closed by a thermally insulated door

20 suitably hinged to the cabinet 10. In order to cool the air within the food storage or refrigerated compartment 19, there is provided an evaporator or cooling unit 11 of any suitable type, preferably disposed in the upper portion of the compartment 19. I have illustrated an evaporator, the open front end of which is closed by a door or closure member 12. Below the cooling unit 11 there is disposed a receptacle 13, such as a meat pan, comprising a lower food supporting member 21 and an upper cover member 22.

In order to support the receptacle, there is provided a support or frame 14 in the form of a pair of spaced-apart longitudinally extending track members 14a disposed along each side of the cooling unit and including a plurality of vertically spaced-apart ledges 23 in order to provide a plurality of selective vertical positions for the lower member 21 of the receptacle or meat pan. This selective positioning arrangement of the member 21 permits disposition of the pan according to the sizes of articles to be stored therein as well as providing means for choosing the amount of ventilation for the interior of the receptacle. In the form of my invention illustrated in the drawing, the members 14a comprising the frame 14 are supported from the top wall 24 of the compartment 19 by means of a plurality of rods 15, one of such rods being disposed in the vicinity of each corner of the evaporator 11. The rods or supporting members 15 may be secured in any desired fashion. For example, the rods, as best seen in Fig. 2, have been secured to the members 14a by means of welding after being inserted through suitable openings in the laterally extending flange 16 thereof. If desired, however, the rear rods may be eliminated and the frame supported from the rear wall of the refrigerated compartment, or the frame may be supported entirely from the inner liner.

In order to support the cover member 22 of the food storage receptacle I have provided a supporting member 25 having an inwardly extending flange 26 and an upwardly or vertically directed wall 27. The members 25 are secured to the laterally extending portion 16 of the members 14a in any suitable manner as by welding, for example. In order to lend strength to the frame, the members 25 may be joined at the rear, as by a member 29, which may be an integral part of members 25. A member 30 having a vertically extending portion 36 and an inwardly extending portion 31 terminating in an offset and inwardly extending portion 32 is pivotally supported from the front portion 28 and the rear portion 29 of the vertical wall 27 of the member 25 as by means of a pin 33 extending through suitable openings in the end walls 28 and 29, respectively. The portion 32 is formed and constructed to have engagement with the inwardly directed flange 26 and is offset with respect to the portion 31 a sufficient distance to provide a substantially horizontal support for the cover member 22.

In some cases, it may be desired to invert the cover portion 22 and use that member for the storage of frozen molds, ice cubes, or perhaps bottled goods or, in some cases, for receiving the drip water during defrosting. To permit this arrangement the cover member 22 and the members 31 and 32 are so dimensioned that the cover member 22 when inverted will be received between the connecting portions 34 joining the inwardly extending portions 31 and 32.

The portions 36, provided to limit the lateral movement of the cover member 22 when used as a cover, extend longitudinally of the cover member on each side thereof and are integral with or may be suitably secured to the upper surface of the portions 31 in any suitable manner as by welding, for example. In order to defrost the evaporator 11 when a predetermined amount of ice has accumulated on the surfaces thereof, I 10 contemplate removing the cover member 22 and moving the hinged or pivotal portion 30 of the frame 14 from the position shown in the full line of Figs. 1 and 2 to the position shown by the dotted lines in Fig. 1. In this position any water 15 or ice falling from the sides of the evaporator 11 will strike the tilted member and guide such material onto the inwardly directed flange 26 of the member 25 and thence into the lower member 21 of the food storage receptacle which may 20 be removed by sliding the parts thereof outwardly through the door opening of the cabinet.

Engagement between the guide means and the vertically extending portion 27 serves to locate the guide means in the defrosting position and, 25 as previously explained, the engagement between the inwardly directed portion 26 and the inwardly directed portion 32 serves to locate the guide means in the cover holding position.

The door or closure member 12 is suitably supported from one of the vertically extending rods 15 as indicated in Fig. 3. I may provide a spring 38 for biasing the door 12 to its closed position. In order to vertically position the door 12 for 35 closing the opening in the front of the evaporator 11 I have illustrated the use of a collar 39 engaging the lower edge of the door.

I have provided a pair of shelves 17 in the space between the meat pan and the side walls of the compartment 19. The shelves may be of 40 any desired construction such, for example, as having a marginal edge formed of suitably sized wire and indicated by the numeral 40 and a plurality of longitudinally extending wires 41 to provide an article supporting surface. The shelves 17 are supported slidably and removably 45 along one side thereof by means of suitable members 42 secured to the side walls of the food storage compartment and on the other side by means of the horizontally extending portions 16 of the frame 14. The vertically extending wall 27 of member 25 cooperates with members 42 to limit 50 the lateral movement of the shelf 17.

Under some circumstances water tends to drip 55 from the evaporator unit during the normal refrigerating cycle. In order to take care of such dripping or in case defrosting takes place without being initiated by the user of the refrigerator as during a power failure, the upper surface of the cover member 22 may be depressed, as indicated by the numeral 43. The rear marginal edge of the cover member may be notched as indicated by the numeral 44 so that any water falling 60 on the surface of the cover member will be directed downwardly over the rear wall of the cover into the lower member 21. The portion or wall 29 will prevent any such water from dripping onto articles in the lower portion of the compartment 19.

70 While I have shown a particular embodiment of my invention, I do not desire my invention to be limited to the particular construction shown and described and I intend in the appended claims to cover all modifications within the spirit 75 and scope of my invention.

What I claim as new and desire to secure by Letters Patent of the United States is:

1. In a refrigerator of the type comprising a thermally insulated cabinet having an inner liner defining a food storage compartment, a cooling element having an opening at the front thereof, a food storage receptacle disposed below said cooling element, means for supporting said receptacle from the top wall of said inner liner, closure means for closing the opening in said element, and means for supporting said closure means from said supporting means.

2. In a refrigerator of the type comprising a thermally insulated cabinet having an inner liner defining a food storage compartment, a cooling element having an opening at the front thereof, a food storage receptacle disposed below said cooling element, means for supporting said receptacle from the top wall of said inner liner, closure means for closing the opening in said element, and means for supporting said closure means from said top wall.

3. In a refrigerator of the type comprising a thermally insulated cabinet having an inner liner defining a food storage compartment, a cooling element having an opening at the front thereof, a food storage receptacle disposed below said cooling element, means for supporting said receptacle, said means including a frame having an opening for receiving said receptacle, means for supporting said frame from the top wall of said inner liner, closure means for the open end of said element, and means associated with said supporting means for supporting said closure means.

4. In a refrigerator of the type comprising a thermally insulated cabinet having an inner liner defining a food storage compartment, a cooling element having an opening at the front thereof, a food storage receptacle disposed below said cooling element, means for supporting said receptacle including a frame having an opening for receiving said receptacle, means for supporting said frame from said inner liner, closure means for said opening in said element, means for carrying said closure means from said supporting means, shelf means, and means for supporting said shelf adjacent said frame, said frame being constructed and arranged to serve at least in part as said shelf supporting means.

5. In a refrigerator having a food storage compartment, a cooling element having an opening at the front thereof, a food storage receptacle disposed below said cooling element, means for slidably and removably carrying said receptacle, said means including a frame and means for supporting said frame from the top wall of said compartment, closure means for said opening in said cooling element, means for carrying said closure means from said supporting means, shelf means, and means for supporting said shelf means adjacent said frame, said frame being constructed and arranged to serve at least in part as said shelf supporting means.
- 10 6. In a refrigerator having a food storage compartment, a cooling element having an opening at the front thereof, a food storage receptacle disposed below said element, said receptacle comprising a lower food supporting member and an upper cover member, means for slidably and removably carrying said receptacle including a frame, said frame comprising a first portion arranged for supporting said lower member and a second portion arranged for supporting said cover member, said second portion being hingedly associated with said frame whereby said second portion may be swung to an outwardly extended position for guiding moisture and ice incident to the defrosting of said element into the lower member.
- 15 7. In a refrigerator having a food storage compartment, a cooling element having an opening at the front thereof, a food storage receptacle disposed below said element, said receptacle comprising a lower food supporting member and an upper cover member, means for slidably and removably carrying said receptacle including a frame, said frame comprising a first portion arranged for supporting said lower member and a second portion arranged for supporting said cover member, said second portion being hingedly associated with said frame whereby said second portion may be swung to an outwardly extended position for guiding moisture and ice incident to the defrosting of said element into the lower member, and means for locating said second portion in its cover holding position and also its guiding position.
